TRANSPOSING KEYBOARD

Elford L. Hanson, Jr., Athens, Ga.

Application December 6, 1938, Serial No. 244,279

3 Claims. (Cl. 84—447)

This invention relates to new and useful improvements in movable keyboards adapted for use in keyboard instruments, whereby transposition of music from one key to another may be accomplished by simple mechanical manipulation and more particularly the invention has reference to a movable keyboard for pianos.

The underlying principle involving movement of a mechanism for producing tones, as the key 10 and hammer lever assembly of a piano, to the right or the left for the purpose of transposing is known in the art, and instruments using this principle have found widespread usage in such fields as composing and various simplified teaching practices. The instruments in use, however, are cumbersome and have left much to be desired in the way of simplicity of operation. Additionally, such devices have a wide field of use for persons having the ability to play in the single 20 key of C and having difficulty adapting themselves to the other keys having complex signatures. The instrument is adjusted to produce music in any desired key although the composition the operator reads is written for fingering in the key of C. It is well known that a large 25 number of compositions contain modulations, that is, the shifting of the music from one key to another during the course of the composition, and for that reason it is necessary for the movable keyboard to be shifted to the desired key in such an easy and smooth manner that little or 30 no interruption in playing would be perceptible. In the instruments of this type known in the prior art, too much time was required to shift the position of the keyboard during a performance involving modulation.

The object of the present invention is to provide a keyboard that may be shifted silently and smoothly from one key to another by a simple operation involving the use of only one hand.

A further object of the invention is to reduce to a minimum the number of moving parts necessary for the operation of a transposing keyboard.

The operation of the present keyboard is simple and the transposing features thereof cannot affect the playing of one who wishes to use the instrument in conventional manner. It is so constructed that music may be pitched to any one of the fifteen keys without causing complexity in the playing or reading of music. With instruments of this kind it is only necessary to learn to play in the key of C. While all music may be played by operative manipulation suitable to playing in this key, the actual tones produced will be those of the key in which the composition was intended to be played. Playing on an instrument as hereinafter described renders unnecessary the ability to read music in the scales of keys other than that noted above, and the only sharps 50 or flats which are used are those that are added

to the particular key in which the music is written.

In its preferred embodiment, the present invention contemplates a rigid framework supporting a number of key levers in excess of those normally used which are mounted above the conventional hammer levers and made free to move across such hammer levers by means of anti-friction rollers. The movement of said key lever system is actuated by an adjustment lever rigidly 10 connected to the key lever framework and projecting through an opening in the panel board, which in turn is calibrated to correspond to the keys in which the instrument may be played. Movement of the key lever system is accomplished by disengaging the adjustment lever from a suitable locking device and moving the same to the right or to the left until in register with the notation corresponding to the desired key. The keyboard is then in position to play in that key 20 in which the music is to be played.

As may be seen from the drawings, the system is so designed that only a minimum portion of the keyboard system is moved. This naturally facilitates the movement thereof, which may be accomplished by only a slight pressure upon the adjustment lever. The framework supporting the key lever is made sufficiently rigid to eliminate any distortion due to torque which might ensue from the movement of the keyboard by the adjustment lever. As may be seen by consideration of the following detailed description, distortion of the device as a result of torque due to movement of the key lever system would reduce the efficiency of the instrument as a whole and, in extreme cases, render the instrument incapable 35 of proper operation.

The invention will be fully understood upon consideration of the following description of one specific embodiment thereof in connection with 40 the attached drawings, wherein:

Fig. 1 is a fragmentary plan view of a piano with the cabinet broken away to show the hammer levers and the relation of the key levers thereto;

Fig. 2 is a fragmentary section through the 45 keyboard to show the adjustable support for the keyboard and the relation of key levers to hammer levers;

Fig. 3 is a fragmentary elevation of the front panel of a piano showing the means for positively 50 retaining the keyboard in a desired position;

Fig. 4 is a fragmentary elevation on line 4—4 of Fig. 2;

Fig. 5 is a fragmentary section on line 5—5 of Fig. 2;

Fig. 6 is a front elevation of a piano having the 55 device of this invention incorporated therein; and

Fig. 7 is a top plan view of the piano illustrated in Fig. 6.

As seen in Fig. 1 the operative mechanism to 60

cause the hammers to strike the respective strings of the instrument comprises key levers 10 and hammer levers 11, which are preferably weighted with lead at portions 12 and 13, respectively, to 5 balance the levers and equalize the actions of black and white keys. At any time when the instrument is in position for playing in a given key, the relationship and operation of the mechanisms to cause strings to be struck are conventional.

Each hammer lever 11 rests on a wooden block, supporting felt pad 14, which acts as a fulcrum to operate the striking mechanism indicated generally at 15 when the head of the adjustable pin 16 is struck by the key lever. Suitable pivot and guide pins 17 and 18 are secured to fixed parts of the piano chassis 19 and work in felt lined slots 20 and 21 in the hammer lever. Felt shock absorbers are placed at those points where 20 cushion effects might conceivably set up vibration in the chassis 19, as for example at 22.

The position and nature of adjustable pins 16 are important to the specific embodiment of my invention here disclosed, but it will be clear as 25 the disclosure proceeds that in its broader aspects the invention contemplates other suitable means for accomplishing a similar result.

According to the present invention, the key levers are supported in any desired position with 30 respect to the hammer levers by a superstructure readily movable with respect to chassis 19. In the illustrated embodiment the said superstructure comprises a series of three U-shaped pieces of cold rolled steel 23, 24 and 25, each securely 35 fastened to a steel strip 26 at either end of the keyboard. The forward U-shaped piece 23 rides on three anti-friction rollers 27 and the rearward U-shaped piece 25 rides on two similar rollers 28 and each of the said rollers is mounted on the 40 chassis 19. To maintain the superstructure in proper parallel relationship to the chassis, guide posts 29 and 30 are mounted on the said chassis at suitable intervals along the keyboard.

The entire operative assembly of key levers 10 is mounted on the said U-shaped pieces 23, 24 and 45 25. Piece 25 supports a series of pivot pins 31, each pin 31 fitting in a corresponding guide slot 32 in a key lever 10 which slot is preferably felt lined. A felt washer 33 about the base of each 50 pin 31 serves as a fulcrum for the corresponding key lever 10. It will be noted that the pivot pins 31 for white key levers are somewhat further forward than the similar pins for black key levers. Usually, a difference in position of about $\frac{1}{8}$ of an 55 inch is proper although this may vary with the instrument under consideration. Such difference in position of the pivot point is advisable in order to insure uniform operation of the several key levers. Guide pins 34 operating within guide slots 60 35 of the black key levers are secured to U-shaped piece 24, while similar guide pins 36 are secured to U-shaped piece 23. Guide slot 37 and felt pad 38 are of more or less conventional construction.

It will be readily understood that the super- 65 structure can be shifted to right or left in order that the key levers 10 will be placed in position to operate different hammer levers 11 by striking the heads of adjustable pins 16. The heads of the said pins are preferably rounded and the 70 under surface of each key lever is fitted with a wear resistant plate 39 which may be of metal, a synthetic resinous material or the like.

As shown in Fig. 4, the keyboard comprises a 75 number of key levers in excess of the number of hammer levers, namely 11. In all instruments

using this type of keyboard it is necessary to include six extra keys on the left of the keyboard and five on the right of the keyboard in order to maintain the normal number of keys in view at all times. The keys which are not in position to contact adjustable pins 16 are hidden from view of the operator by a masking panel 51 and the key levers under the said masking panel are supported in position to move over the pins 16 upon shifting of the superstructure by a track 40 secured to the 10 piano chassis. The track 40 is of a length sufficient to accommodate the full number of key levers in excess of the number of hammer levers. It will be noted that under some conditions, the masking panel 51 will overlie half of one key lever. 15 However, the position of the hammer levers is such that a key only partially exposed may be ignored by the person playing the instrument.

For shifting the keyboard to a desired position and securing the same in such position, I provide 20 an adjusting lever of novel design. A strip of cold pressed steel 41 is securely attached to the superstructure at the central portion thereof. Preferably the strip 41 is bolted to the underside of U-shaped piece 25 and connected by an angle 25 strip 42 to the U-shaped member 24. A U-shaped piece 50, of a width preferably less than that of the other members of the key supporting superstructure, extends between the parts 26 at each 30 end of the frame. As shown in Fig. 2, the connection between strip 41 and angle strip 42 is by means of a bolt passing through piece 50, whereby substantial rigidity is imparted to the superstructure. It will be noted that the piece 50 serves the further purpose of preventing the key levers from 35 rising off their respective pivot pins. Suitable felt washers are inserted between metal to metal contacts wherever necessary to damp vibrations which would interfere with the music produced by the instrument. The strip 41 is extended upwardly behind the front panel of the instrument and is bent forward at its upper end to form an operating handle 43.

In the region of the front panel through which the handle 43 projects to the exterior of the 45 instrument there is affixed a plate 44 having a horizontal slot 48 of a width to accommodate the handle 43. The said handle is equipped with a hingedly mounted catch member 45 adapted to oscillate within a groove in the upper surface 50 of handle 43 and a spring 46 is inserted to force member 45 upwardly to engage one of the notches 47 in the upper edge of slot 48. The notches 47 are suitably marked to indicate the key in which the instrument will play when the keys are struck 55 in the manner appropriate for playing the particular composition in the key of C. Care should be exercised in constructing the adjusting features of the superstructure to avoid interference with the hammer levers 11. If necessary, the 60 upper surfaces of the hammer levers may be notched to permit free movement of the superstructure and strip 41 without contacting the hammer levers.

It will be noted that the indicia on the plate 65 44 are suitable for setting the instrument to play in any major key while using the conventional fingering for playing in the key of C major. It is to be understood that this is exemplary of the nature of the invention.

The operation of devices made in accordance with this invention will be obvious to those skilled in the art to which it appertains. By grasping the handle 43 in a manner to depress catch 45 and exerting relatively little force the entire key- 75

board is quickly and easily shifted to a desired position.

In utilizing the advantages of this invention, the compositions to be played are written in the key of C with suitable indication on the music as to the key in which it is intended to be played. The musician then sets the keyboard to the desired key and plays the composition using the same fingering as that usual for the key of C.

5 10 15 20 25 30 35 40

Many uses of the present invention will be immediately recognized by those skilled in the art. For example, a musician would be aided in transposing a composition to a key other than that in which it is written. Thus in order to transpose music for use in playing an accompaniment to a voice or musical instrument, the range of which does not correspond to the music as written, the accompanist may make proper adjustment of the keyboard and proceed to play the music in a suitable key with far less inconvenience than is normally involved in such operations.

There are many skilled musicians who are unable to transpose satisfactorily while playing from written music. It will be noted that the difference 25 between any two adjacent positions indicated on the plate 44 is a half tone. In order to transpose music from the key in which it is written to any desired key, it is only necessary to count the number of half tones between the basic notes of the two keys and move the keyboard a corresponding number of notches to right or left as the case may be and play the music with the fingering appropriate to the key in which it is written.

While the invention is susceptible of various modifications and changes, I have herein described in detail the preferred embodiment, but it is to be understood that I have not thereby intended to limit the invention to the specific form disclosed but intend to cover all the modifications falling within the scope of a keyboard instrument, such as a pipe organ, electric organ, piano accordion, and a so-called steam piano.

I claim:

1. In a piano having a chassis, a plurality of tone producing strings thereon, a plurality of horizontal hammer levers each adapted to cause one of said strings to sound also mounted on said chassis and a number of horizontal key levers in a keyboard movable across said hammer levers in such manner that a major proportion of said key levers overlie said hammer levers in parallel relation thereto, some of said key levers being shorter than the remainder thereof, there being one key lever above each hammer lever having means on the underside thereof to make contact with and depress said hammer lever upon depression of said key lever; a frame movable with respect to said chassis and a mounting therefor comprising a pair of rigid horizontal bearing members each having an upturned edge at each end thereof of a length substantially greater than that of the keyboard one disposed at the forward and one at the rear side of said frame, a pair of rigid straight members rigidly connecting the respective upturned ends of said bearing members at the ends of the keyboard, a longitudinal rigid member parallel to and intermediate said bearing members rigidly connected at its ends to said straight members, guide pins 5 10 15 20 25 30 35 40 45 50 55 60 65 70

on said rear bearing member and corresponding guide slots in said key levers, guide pins on said longitudinal member and corresponding slots in said shorter key levers, guide pins on said forward bearing member and corresponding slots

in said remainder of said key levers to retain said key levers on said frame in operative position, rollers mounted on said chassis to support said bearing members for movement in the direction of the length of the keyboard, means to inhibit movement of said frame in a direction at right angles to the length of the keyboard and means to retain said frame in a desired position with respect to said chassis.

2. In a piano having a chassis, a plurality of tone producing strings thereon, a plurality of horizontal hammer levers each adapted to cause one of said strings to sound also mounted on said chassis and a number of horizontal key levers in a keyboard movable across said hammer levers in such manner that a major proportion of said key levers overlie said hammer levers in parallel relation thereto, there being one key lever above each hammer lever having means on the underside thereof to make contact with and depress said hammer lever upon depression of said key lever; a frame movable with respect to said chassis and a mounting therefor comprising a pair of rigid horizontal bearing members each having an upturned edge at each end thereof of a length substantially greater than that of the keyboard one disposed at the forward and one at the rear side of said frame, a pair of rigid straight members rigidly connecting the respective upturned ends of said bearing members at the ends of the keyboard, guide pins on said bearing members and corresponding guide slots in said key levers to retain said key levers on said frame in operative position, rollers mounted on said chassis to support said bearing members for movement in the direction of the length of the keyboard, means to inhibit movement of said frame in a direction at right angles to the length of the keyboard and means to retain said frame in a desired position with respect to said chassis.

3. In a keyboard instrument having a chassis, a plurality of tone producing elements thereon, a plurality of horizontal operating levers each adapted to cause one of said tone producing elements to sound also mounted on said chassis and a number of horizontal key levers in a keyboard movable across said operating levers in such manner that a major proportion of said key levers overlie said operating levers in parallel relation thereto, there being one key lever above each operating lever having means on the underside thereof to make contact with and depress said operating lever upon depression of said key lever; a frame movable with respect to said chassis and mounting therefor comprising a pair of rigid horizontal bearing members each having an upturned edge at each end thereof of a length substantially greater than that of the keyboard one disposed at the forward and one at the rear side of said frame, a pair of rigid straight members rigidly connecting the upturned ends of said bearing members at the respective ends of the keyboard, guide pins on said bearing members and guide slots in said key levers to retain said key levers on said frame in operative position, rollers mounted on said chassis to support said bearing members for movement in the direction of the length of the keyboard, means to inhibit movement of said frame in a direction at right angles to the length of the keyboard and means to retain said frame in a desired position with respect to said chassis.
